CHARLES H. FOSTER, OF ST. LOUIS, MISSOURI.

RANGE-BOILER STAND.

No. 909,777.

Specification of Letters Patent.

Patented Jan. 12, 1909.

Application filed August 28, 1908. Serial No. 450,647.

To all whom it may concern:

Be it known that I, CHARLES H. FOSTER, a citizen of the United States, residing at St. Louis, State of Missouri, have invented certain new and useful Improvements in Range-Boiler Stands, of which the following is a full, clear, and exact description, reference being had to the accompanying drawings, forming a part hereof.

10 My invention has relation to improvements in boiler-stands; and it consists in the novel construction of stand more fully set forth in the specification and pointed out in the claims.

15 In the drawings, Figure 1 is a side elevation of the stand; Fig. 2 is an end elevation thereof; Fig. 3 is a horizontal section on the line 3—3 of Fig. 1; Fig. 4 is an enlarged vertical longitudinal section on line 4—4 of Fig. 20 3, the bases of the standards being shown in side elevation; Fig. 5 is a vertical cross-section on the line 5—5 of Fig. 4; Fig. 6 is a top plan of one of the supporting standards; and Fig. 7 is a perspective of the lower end 25 of the supporting standard.

The object of my invention is to construct a range-boiler stand which shall occupy a limited amount of floor space; one which can be readily assembled and taken apart; one 30 capable of ready adjustment for various sizes or diameters of boilers; one which can be assembled without the use of bolts, rivets, or similar fastening devices; one which can be cheaply manufactured, contain a minimum 35 number of parts, and one possessing further and other advantages better apparent from a detailed description of the invention which is as follows:

Referring to the drawings. B, represents a 40 suitable oblong base or casting provided with terminal legs L and side legs L', the latter inclining so as to bring the several legs within the limits of a common circumscribing circle, such circle representing the 45 maximum floor space taken up by the supporting base of the stand. Formed along the middle of the upper edges of the sides of the oblong base B are depressions d, on either side of which are formed a series of 50 shallow grooves or depressions 1, 1. On the lower edges of the side walls of the base, immediately below the central depression d and extending to points opposite the first of the series of grooves 1 on either side of said 55 depression d are a series of V-shaped notches 2, 2, the spaces between the notches and end

walls of the oblong base being occupied by suitably spaced lugs or projections 3, 3, the terminal lugs 3' being preferably formed wedge-shaped as shown by reason of their 60 close proximity to said end walls.

The standards 4 by which the range-boiler R is directly supported, are cast in the shape substantially as shown in the drawings, the upper ends of the standards being formed with laterally projecting arms 5 having ledges a engaging the raised bottom of the boiler, and terminating in fingers b which engage the base of the peripheral walls of the boiler. Each standard 4 terminates at 70 the bottom in a locking leg or projection 6 of wedge - formation, the sides of the wedge terminating at the top on each side in trunnions 7 which are adapted to rest in a pair of oppositely disposed recesses 1, 1; the base 75 of the inner face of the wedge terminates in lugs or extensions 8, 8, which engage a pair of oppositely disposed V-shaped notches 2; and the lower edge of the outer face of the wedge terminates in extensions or lugs 9, 9, 80 which are adapted to engage an adjacent pair of lugs 3, 3, and thus prevent accidental displacement of a standard when once locked in place on the base B. The sides of the leg 85 6 are cut away or removed a depth indicated by the offset or shoulder s in order to allow for the presence of the middle lug 3, which naturally will occupy the space thus provided for it when the standard is shifted to 90 rest in the outermost pair of grooves 1, 1, in which case the extensions 9, 9, will engage the terminal lugs 3', 3'.

In order to lock the standard in position, the same is turned slightly to allow the leg 6 to pass freely between the side walls of the 95 base B, whereupon it is turned so as to bring the trunnions 7, 7, into their corresponding pair of depressions 1, 1, the extensions 8, 8, being made to engage their corresponding pair of recesses 2, 2. To prevent accidental 100 displacement of the standard by an inward tilting thereof, the extensions 9 will strike their adjacent lugs 3 (3') (Fig. 4) and thus arrest an undue movement in this direction. It will be seen that each standard is inclined 105 not only to the vertical plane of the middle longitudinal axis of the base B, but to the corresponding vertical plane of the transverse axis, so that when the pair of standards are in place, the terminal fingers b, b, will be 110 disposed on the perimeter of the same circle (representing in Fig. 6, the outer curve of

the boiler), thus permitting the several fingers *b* (four in number) to simultaneously engage the outer wall of the boiler supported between them. Whether the standards 5 occupy positions represented by the middle grooves 1, 1, or the inner or outer grooves (dotted positions Fig. 1), the fingers *b* will always fall on the arc of the circle representing the cross-section of the boiler.

10 Of course, for a small circle, a greater portion of such circle will be engaged by the fingers than would be the case for a large circle. This is quite obvious since the arcs of a great number of circles may pass 15 through the same two points.

The present stand possesses great stability, one reason therefor being that the standards 4, 4, converging as they do toward a common point within the base *B*, center the load well 20 within the area of the supporting legs *L*, *L'*. The entire stand is composed of three pieces, viz., one base and two standards, and may be readily packed for shipment.

Having described my invention, what I 25 claim is—

1. In combination with a base, a pair of standards detachably locked thereto on each side of the center thereof, and inclined to vertical planes disposed along intersecting 30 axes of the base, said standards terminating at the top with parallel disposed arms, substantially as set forth.

2. In combination with an oblong base provided with series of upper depressions 35 on the sides thereof, and with notches at the lower edges of said sides and having lugs disposed on the inner faces of the sides contiguous to the notches, a pair of standards having locking legs provided with upper 40 terminal trunnions for engaging the depressions, inner basal lateral extensions for engaging a pair of oppositely disposed notches, and having outer basal extensions for engaging the lugs to prevent accidental displacement of the standards, the latter being inclined from opposite directions to the vertical planes of the middle longitudinal and transverse axes of the base, and provided with upper laterally projecting parallel 45 arms terminating in fingers, substantially as set forth.

3. In combination with an open base, provided with opposing walls having upper depressions and bottom notches, a pair of 50 standards having basal locking legs, and means on the legs for simultaneously engaging said depressions and notches, substantially as set forth.

4. In combination with an open oblong 55 base provided on its side walls with upper

depressions and bottom notches, a pair of standards having basal legs, and lateral trunnions and extensions respectively engaging the depressions and notches aforesaid, and means on the side walls of the base and 60 on the legs for preventing accidental displacement of the legs when once engaged, substantially as set forth.

5. In combination with an oblong base having its side walls provided with upper depressions and bottom notches, a pair of standards inclined to the vertical planes of the longitudinal and transverse axes of the base, terminal legs on the standards having lateral trunnions and basal extensions for engaging the depressions and notches aforesaid, lugs disposed on the inner faces of the side walls contiguous to the notches, and an additional pair of extensions formed with the legs for engaging the lugs to prevent 75 undue tilting and displacement of the standards when once in locked position on the base, the upper ends of the standards being provided with arms extending in parallel relation but in opposite directions and terminating in fingers, substantially as set forth.

6. In a stand, a pair of standards inclined toward a common axis from opposite directions, and terminating in parallel arms extending in opposite directions toward a vertical plane passing through said axis, said arms having upwardly projecting fingers at opposite ends thereof disposed on the perimeter of a common circle, substantially as 95 set forth.

7. In combination with a base composed of an open frame, a pair of standards, legs at the ends of the standards, and means on the base and legs respectively for securing 100 the latter to the base at different distances from the center of said base, substantially as set forth.

8. In combination with a base composed of an oblong frame, a pair of standards, legs forming the lower terminals of the standards and disposed in the general plane of but inclined to the general direction of the standards, and means on the side walls of the base and legs respectively for locking 110 the latter to the former at different distances from the transverse center of the base, substantially as set forth.

In testimony whereof I affix my signature, in presence of two witnesses.

CHARLES H. FOSTER.
